UNITED STATES PATENT OFFICE.

PHILIP B. WALLACE AND FRANK H. FOX, OF SAN FRANCISCO, CALIFORNIA; SAID FOX ASSIGNOR TO SAID WALLACE.

BENDING MACHINE.

Application filed September 22, 1920. Serial No. 411,895.

To all whom it may concern:

Be it known that we, PHILIP B. WALLACE and FRANK H. Fox, citizens of the United States, residing at San Francisco, in the 5 county of San Francisco and State of California, have invented new and useful Improvements in Bending Machines, of which the following is a specification.

The present invention relates to improvements in machines for bending pipes, tubes, rods, and the like, into coils and other shapes.

An object of the invention is to provide a machine of the character described with 15 which pipe, etc., of various sizes may be more quickly and accurately bent or shaped without distorting the pipe and without necessitating the heating thereof; the machine being simply constructed and arranged whereby strength of construction and ease and facility of operation are provided.

The invention possesses other advantages and features, some of which, with the foregoing will be set forth at length in the following description wherein we shall outline in full that form of the invention which we have selected for illustration in the drawings accompanying and forming a part 30 of the present specification. In said drawings, we have shown one form of the construction of our invention, but it is to be understood that we do not limit ourselves to such form, since the invention as expressed in the claims may be embodied in a plurality of forms.

Referring to the drawings:

Figure 1 is a top plan view of the machine of this invention.

Fig. 2 is an enlarged fragmentary sectional view partly in side elevation of the pipe clamp or vise, showing a piece of pipe held therein.

Fig. 3 is an enlarged fragmentary sectional view partly in side elevation of the bending block and operating means therefor.

Fig. 4 is a side elevation of the machine.

Fig. 5 is a sectional view taken on the 50 line 5—5 of Fig. 4.

Fig. 6 is a fragmentary vertical sectional view taken through Fig. 5.

Fig. 7 is an enlarged fragmentary plan view of a detail of the invention.

Fig. 8 is a side elevation partly in section of a detail of the invention. 55

Fig. 9 is a top plan view of a modified form of the invention.

Fig. 10 is a fragmentary side elevation of a detail of the modified form. 60

Referring to the present embodiment of the invention as illustrated in the accompanying drawings, the machine comprises a table or base 1 having legs 2 secured to a suitable base. A plate or frame 3 is 65 mounted above the base 1 in spaced parallel relation thereto, being supported at one end by a vertical post 5, which post is fixed to the base 1. A pipe clamp or vise 6 is adjustably mounted on the frame 3 so as to hold the pipe while it is being bent around a form 7, which latter is secured to the post 5. Levers 8 and 9 are each pivoted to the post and the lever 8 carries a pressure block 10, which block engages and bends the pipe 75 around the form as the levers are swinging on their pivots. The form is removable and the pressure block is radially adjustably mounted on the lever 8 whereby different sizes of pipe may be handled and various 80 shapes produced.

The levers 8 and 9 are power operated and may be driven by any suitable drive or operating means, although we prefer the gear drive from a motor as shown in the 85 drawing. This drive comprises an electric motor 11 mounted on a base 12 to one side of the table 1. The motor shaft 13 carries a pinion 14 which meshes with a gear 15 that is carried by a worm shaft 16 which worm shaft is journaled in suitable bearings in the table 1. The worm shaft 16 meshes with a worm wheel 17 on a vertical shaft 18 which vertical shaft extends up through the table 1 and on its upper end 95 carries a pinion 19. The pinion 19 meshes with a large main gear 20, which gear is rotatably mounted on the post 5 below the frame 3. The lever 9 is open and the upper and lower sides thereof are pivoted to the post 5 above and below the main gear 20, which latter extends between said sides, whereby the lever operates in the plane of the gear. A clutch block 22 is longitudinally adjustably mounted in the lever 9 and has a toothed side 23, adapted to mesh with the teeth of the gear 20. The clutch block is operated by an L-shaped lever 24 pivoted

intermediate its end on a pin 24' on the lever 9. A link 26 is pivoted to the block and to a swinging plate 26' attached to the pin 24' so that when the lever is raised upwardly, the block will be pushed inwardly and will engage the gear 20. The lever 24 projects outwardly beyond the lever 9 so as to facilitate the operation thereof. Adjustable means is provided for automatically declutching the lever 9 so as to prevent it from being moved entirely around with the gear 20 and to regulate the bending action. This means comprises a bar 27 adjustably mounted upon the lever 9 and at one end of which there is a downwardly opening hook portion 27a. A pin 27b is engaged in the hook portion 27a and joins the inner end of the lever 24 with the plate 26'. The bar 27 has slots 28 therein, thru which slots bolts 29 extend so as to slidably hold the bar in place. A rocker member 30 is pivoted as at 31 upon the lever 9 so that one end thereof engages the inner end of the bar 27. The other end of the rocker carries a release member 32 pivoted as at 33 at one end to the rocker and having a notch 34 in its outer end.

A leaf spring 35 tends to force the member 32 inwardly against a stop pin 36 on the rocker. A detent or trip member 37 is adjustably held on the frame 3 by set screws 37', and is in the path of the notched end of the release member 32. The trip 37 is actuatedly movable concentric with the axis of the main gear whereby the lever 9 may be made to travel to the desired extent before the automatic declutching takes place. This is varied to suit the particular work by changing the position of the trip or detent. When the trip or detent engages the release member, the rocker is rocked and pushes the bar 27 outwardly. This, through the lever 24 causes the block 22 to be pushed out of contact with the gear 20 and allows the gear to rotate without moving the lever 9.

The lever 8 is open and formed of two parts with the inner ends of said parts pivoted as at 38 to the shaft 5 and extending above and below the form. A link 39 is pivoted at its ends to, and connects, the outer ends of the levers 8 and 9 so as to communicate the pulling force to the lever 8. The bending or pressure block 10 is slidably mounted between the parts of the lever 8 and is adapted to move in an arc around the form, which latter, in this instance, is semi-annular. The block 10 is provided with a pipe receiving groove 40 curved in cross section to permit the pipe to snugly engage in the groove. A holder block 41 is slidably mounted in the lever 8 outward of the pressure block 10 and at its inner face is recessed as at 42 so to receive and hold the pressure block 10 in place. The

holder 41 is recessed as at 43, said recess opening out on one side face and on the outer face of the holder. An L-shaped lever 44 is pivoted at the end of its shorter angular portion as at 45 to a block 46 in the lever 8. This lever 44 has a projection 47 intermediate of its ends and said projection is rounded, as at 48, at its free end. This rounded end is adapted to engage the inclined inner wall 49 of the recess 43. The recess is so cut that the projection will be past center when in the position shown in Fig. 3, whereby the lever will have no tendency to be forced out of the recess 43 during the bending operation. The holder and block 46 are provided with retaining flanges 50, which flanges engage the side edges of the upper and lower parts of the lever 8 and hold the holder and block 46 securely in the lever 8. The block 46 is adjustable longitudinally of the lever and its adjustment is regulated by a screw 51 turned through a member 52, which member is held adjustably on the arm 8 by bolts 52a. The screw 51 has an angular head 53 to permit of the turning thereof with a suitable tool. The other end of the screw abuts the block 46. These adjustments are provided to accommodate the pressure block and associated parts to pipes of various sizes.

The vise or pipe clamp comprises a block 55 slidable upon the frame 3 near one end of the form. The frame has a longitudinal slot 56 in which a bolt 57 is slidable. The lower end of the bolt has a nut 58 which engages the under face of the frame. The upper end of the bolt is turned in a threaded opening 58' in the block 55. By tightening the nut, the block will be held in adjusted position. One side of the block 55 has an extension 59 formed with a transverse pipe receiving groove 60. A flexible chain 61 is pivoted at one end as at 62, within a recess 63 in the lower part of the block under said extension. The chain extends upwardly over the top of the block and on the rear face of said block is removably fastened to an adjustable hook 63. The hook 63 is threaded and turned in an opening therefor formed in an ear 64 provided on said block. In the top of the block 55 an eccentric member 65 is mounted so that the chain extends over the top of said member. An operating lever or handle 66 is provided for said eccentric so as to take up or let out on the chain, dependent upon the movement of the eccentric. Pipe to be bent is placed in the pipe receiving groove 60 and the chain is extended around said pipe so as to engage it as shown in Figure 2. By now turning the eccentric in the proper direction, the chain will be caused to grip the pipe and will effect a secure holding thereof so that the bending operation may be effectively carried out.

To prevent the block 55 from slipping, there is provided a stop member 67 which may be a length of pipe or a bar or rod. This member 67 is laid upon the frame 3 with 5 one end thereof in engagement with the rear of the block 55 and its other end is engaged with an adjustable stop screw 68. The screw 68 is mounted in a lug 69 carried on the frame and is provided with an angular head 70 which provides for the turning of the screw with a suitable tool, not shown.

In the operation of the machine, the form of the desired size and shape is secured upon the vertical shaft 5 and the vise or pipe holding means is adjusted in the frame 3 so as to be disposed in proper relation to the form. The pipe is then placed in the groove 60 therefor on the block 55 and gripped by the chain 61 so as to be held 15 against slipping in the vise. The levers 8 and 9 are moved around into substantially the position opposite that shown in Figure 1 so as to be in a position to effect a bending of the pipe around the form. The pipe 20 is secured so that it projects beyond the vise and form and will lie between the form and pressure block 10. This block 10 is 25 adjusted into proper position depending upon the size of the pipe to be bent so that the pipe will engage in the groove 40 of the block 10. With the pipe thus arranged, the operator now starts the motor. The clutch operating lever 24 is then pulled upwardly and the clutch block 22 is moved so that the 30 teeth 23 thereof mesh with the teeth of the main gear 20 and the lever 9 will be carried around with the gear. By reason of the link connection of this lever with the lever 8, the latter lever is moved around with the arm 35 40. As the lever 8 moves from left to right, the pressure block 10 presses the pipe inwardly around and upon the form. The trip member 37 is adjusted so as to release the clutch at a point predetermined where- 45 by the bending operation will stop. Thus, as the lever 9 is carried around with the gear 20, and the release member 32 engages the detent or trip 37, by this engagement the rocker member 30 is moved on its pivot 50 so that one end thereof engages and pushes the bar 27 outwardly. This causes the clutch block 22 to move out of clutching position and the lever 9 is disengaged from the main gear 20. Depending upon the 55 shape and size of the bend, this automatic releasing action may be regulated as desired. The declutching may also be manually effected by the use of the lever 24. The regulation is effected by setting the detent at 60 various points in the path of the releasing member 32. After one bending operation, the arms may be turned by hand to starting position and another bend given to the pipe after loosening the vise and adjusting the 65 pipe relative to the vise. By reason of the

fact that both of the arms 8 and 9 have a common pivot on the post 5, and the form and gear 20 are likewise at their centers fastened to this vertical post, the bending apparatus is compactly arranged and functions so that the bending takes place effectively and accurately and without distorting the pipe.

To release the pressure block 10, the lever 44 is moved outwardly past center line 75 of pressure so that the projection 47 of the lever 44 is moved out of the recess 43. This permits the holder 41 to be moved outwardly on the arm 8, and permits of disengagement of the pressure block from the pipe. When 80 other sized pipe is used, another suitably grooved block is provided and interchangeability of the block is provided for by the construction of the holder in which the block is removably mounted.

Referring particularly to Figures 9 and 10, the modified form of the invention illustrated therein comprises a base 71 having a frame 72 extending in super-posed parallel relation thereto. Upon the base 71 is a 90 motor 73 connected by suitable gearing 74, after a manner which it is not believed necessary to illustrate in detail, with the main drive gear 75. This gear 75 is mounted upon a vertical post 76 supported by the 95 frame and base. Longitudinally adjustably mounted on the frame 72 is a vise or clamp 77 of the same construction as the vise in the preferred form of the invention. A form 78 is removably mounted upon the shaft 76 100 in any suitable manner. In this modified form of the invention, instead of providing two pressure levers, use is made of a single lever 79 pivoted at the inner end to the shaft 76 and arranged to operate in the plane of 105 the bending form 78. This lever 79 extends considerably beyond the periphery of the gear 75 and is connected with said gear by a link, said link being secured to an intermediate portion of the arm at one end and to a point on the periphery of the gear 75 at its other end. The lever 79 carries a pressure block 81 which moves concentrically about the bending form in the plane of said form. This block 81 is mounted in a holder 82 of 110 the same construction as that of the preferred form except that in this form the holder is provided with a handle 83 to facilitate the release of the lever 84 from pressure position against the block 81, the holder 82 being adapted to be held in place by a lever 84 and associated parts of a construction identical with that of the preferred form of the invention. The lever 84 is pivoted to a longitudinally adjustable block 115 120 125 85, which block is arranged to be moved by a set screw 86. The set screw 86 is adjustable through a block 87, which latter is longitudinally adjustably mounted in the bar 79. The adjustable mounting of the 130

block 87 is effected by use of two pins 88 which are adapted to be inserted through any one of a series of spaced openings in the bar 79 and through the block. In this form, 5 instead of having automatic declutching means, the gearing is provided with a two-way or reversing clutch, generally designated 89 and controlled by a lever and link mechanism 90. In starting the operation, 10 the operator manipulates the clutch member 90 so as to drive the gear 20 from left to right and at the end of the bending operation, for example, after the lever 79 has moved through 90°, the operator manipulates the clutch lever so as to reverse the direction of rotation of the gear 75. This returns the arm to normal position and the operator then declutches the main gear by proper movement of the lever 90 so as to 20 stop the movement of the lever 79.

We claim:

1. A pipe bending machine comprising a frame, a pair of levers having a common pivot on said frame, a form on said frame 25 and around which pipe is adapted to be bent, means for holding the pipe and the frame during bending operation, a pressure block carried by one of said levers and arranged to engage pipe and bend it around said form, 30 means for moving the other of said levers around said form, and a link connecting said levers.

2. A pipe bending machine comprising a frame, a pair of levers having a common pivot on said frame and arranged one above the other, a connection between said levers, a toothed gear on said frame, a clutch block 35 slideable upon one of said levers, means for moving said clutch block into and out of engagement with the gear, a bending form on said frame, a pipe clamp on the frame, and a pressure block on one of said levers arranged to engage and bend the pipe around said form.

3. A pipe bending machine comprising a frame, a pair of levers having a common pivot on said frame and arranged one above the other, a connection between said levers, a toothed gear on said frame, a clutch block 50 slideable upon one of said levers, means for moving said clutch block into and out of engagement with the gear, a bending form on said frame, a pipe clamp on the frame and a pressure block on one of said levers, 55 arranged to engage and bend the pipe around said form, and means for radially adjustably holding said block on said lever.

4. A pipe bending machine comprising a frame, a pair of levers having a common pivot on said frame and arranged one above

the other, a connection between said levers, a toothed gear on said frame, a clutch block slideable upon one of said levers, means for moving said clutch block into and out of engagement with the gear, a bending form on 65 said frame, a pipe clamp on the frame, and a pressure block on one of said levers arranged to engage and bend the pipe around said form, and means operating automatically to declutch said clutch member when 70 said levers have been moved a predetermined distance.

5. A pipe bending machine, a frame, a gear, a vertical member upon which said gear is journaled, a pair of levers each pivoted at one end to said vertical member and being arranged one above the other, a clutch member upon one of said levers, means for moving said clutch member into and out of engagement with the gear, a connection between 75 said levers, a bending form on the frame, and means on one of said levers for engaging and bending pipe around said form, one of said levers operating in the plane of the form and the other in the plane 80 of the gear.

6. A pipe bending machine comprising a frame, a gear mounted horizontally upon said frame, a pair of levers having a common pivot in alinement with the axis of said 90 gear, a form on said frame, one of said levers being arranged to operate in the plane of said form and the other in the plane of said gear, a connection between said levers, a pressure block for engaging and bending 95 pipe around said form carried by one of said levers, a clutch member on the other lever for engagement with the gear, and means for moving the clutch member into and out of clutching position.

7. A pipe bending machine comprising a frame, a gear mounted horizontally upon said frame, a pair of levers having a common pivot in alinement with the axis of said gear, a form on said frame, one of said levers being arranged to operate in the plane of said form and the other in the plane of said gear, a connection between said levers, a pressure 105 block for engaging and bending pipe around said form carried by one of said levers, a clutch member on the other lever for engagement with the gear and means for moving the clutch member into and out of clutching position, and means operating automatically 110 when the gear is rotated a predetermined 115 distance to move said clutch member out of clutching position.

PHILIP B. WALLACE.
FRANK H. FOX.
